Inventors.

UNITED STATES PATENT OFFICE.

JOHN BRELSFORD AND JOHN O. BRELSFORD, OF FREELAND, PENNSYLVANIA.

WASHING-MACHINE.

SPECIFICATION forming part of Letters Patent No. 552,466, dated December 31, 1895.

Application filed May 8, 1895. Serial No. 548,579. (No model.)

To all whom it may concern:

Be it known that we, JOHN BRELSFORD and JOHN O. BRELSFORD, citizens of the United States, residing at Freeland, in the county of 5 Luzerne and State of Pennsylvania, have invented a new and useful Washing-Machine, of which the following is a specification.

The invention relates to improvements in washing-machines.

10 The object of the present invention is to improve the construction of washing-machines, and to provide a simple and efficient one, capable of thoroughly and rapidly cleaning clothes without injuring them and with 15 a minimum amount of labor.

Another object of the invention is to provide a washing-machine which may be readily operated without necessitating the operator assuming an unnatural or irksome 20 position.

25 The invention consists in the construction and novel combination and arrangement of parts hereinafter fully described, illustrated in the accompanying drawings, and pointed out in the claims hereto appended.

30 In the drawings, Figure 1 is an elevation of a washing-machine constructed in accordance with this invention. Fig. 2 is a central longitudinal sectional view of the same. Fig. 3 is a transverse sectional view.

35 Like numerals of reference indicate corresponding parts in all the figures of the drawings.

1 designates a rectangular washing-machine body, supported by suitable legs and 40 provided with a removable cover 2, having a grip or handle and having one edge interlocking with the adjacent portion of the top of the body and secured at the opposite edge by

45 a button. Within the body is journaled a pair of horizontal transversely-disposed shafts 3 and 4, each carrying a pair of sprocket-wheels 5, receiving endless chains 6, to which are secured transverse clothes-carrying slats 7.

50 The slats form an endless apron or carrier and are provided at intervals with projecting pins 8, which engage the clothes and carry them over a rubbing-surface, conforming to the configuration of the endless carrier. The shaft 3 is extended through the front side of the washing-machine body and carries a pin-

ion 9, which meshes with a cog-wheel 10 of a stub-shaft or journal 11, and the cog-wheel is rotated by a crank-handle 12, whereby the endless carrier or conveyer is set in motion. 55

The rubbing-surface of the washing-machine body consists of curved end portions 13 and a yielding rubbing-board 14. The curved end portions are composed of transverse rungs or rods rigidly secured to the sides of the 60 washing-machine body and arranged in a curved line, and the bottom rubbing-board has a corrugated upper face or rubbing-surface and is mounted on supporting-springs 15 and is flexibly connected at its ends to the 65 adjacent portions of the parts 13 by flexible strips 16, which permit the bottom rubbing-board to be depressed and to yield to an excess of clothes accumulating at the bottom of the washing-machine to prevent any liability 70 of the clothes being torn or otherwise injured while being carried over the rubbing-surfaces by the endless conveyer.

In order to increase the rubbing action and to render the washing-machine more effective, 75 the sides are provided with rubbing-surfaces 17, arranged in the space between the endless conveyer and the rubbing-surfaces 13 and 14 and the cover of the washing-machine and consisting of a series of bars arranged in the 80 form of an ellipse. The elliptical rubbing-surfaces, which are disposed in the path of the clothes, are preferably composed of short bars or pieces having curved or convex faces.

The transverse slats, which are secured to 85 the links of the endless chain, may be either flat, as shown in the accompanying drawings, or they may be provided with curved or corrugated faces.

It will be seen that the washing-machine is 90 simple and comparatively inexpensive in construction, that it is capable of thoroughly and rapidly rubbing the clothes being washed, and that the crank may be readily turned to operate the endless conveyer without necessitating the operator assuming an unnatural 95 position.

Changes in the form, proportion, and the minor details of construction may be resorted to without departing from the principle or 100 sacrificing any of the advantages of this invention, such as adapting the gearing to be

readily operated by a treadle instead of a crank, or by a spring, weight, or other form of motor.

What we claim is—

- 5 1. The combination of a body, sprocket wheels mounted on suitable shafts, endless chains arranged on the sprocket wheels, slats carried by the chains and provided with projecting pins and forming an endless clothes carrier, the rods 13 located at the ends of the carrier and arranged in a curved series concentric with the ends of the carrier and spaced therefrom and adapted to confine the clothes and to rub the same, the bed arranged at the 15 bottom of the body between the series of rods 13 and provided with a rubbing surface, and the bars 17 secured to the sides of the body and arranged in elliptical series in the space between the endless carrier, the rods 13, the 20 bed and the top of the body, substantially as described.
2. The combination of a body, sprocket wheels mounted on suitable shafts, endless chains, slats secured to the endless chains and

forming a clothes carrier and provided with 25 projecting pins, the rods 13 arranged in curved series and located at the ends of the clothes carrier, and concentric with the same and spaced therefrom and adapted to confine the clothes, the yieldingly mounted bed arranged at the bottom of the body and located between the series of rods 13, the flexible strips 16 connecting the ends of the bed with the adjacent rods 13 and adapted to prevent the clothes from passing beneath the rods, 30 and the bars 17 secured to the sides of the body and arranged in elliptical series in the path traveled by the clothes, substantially as described.

In testimony that we claim the foregoing as 40 our own we have hereto affixed our signatures in the presence of two witnesses.

JOHN BRELSFORD.
JOHN O. BRELSFORD.
